UNITED STATES PATENT OFFICE.

WILLIAM M. STOCKER, OF WOODHAVEN, NEW YORK, ASSIGNOR TO CAMERON MACHINE COMPANY, OF BROOKLYN, NEW YORK, A CORPORATION OF NEW YORK.

WINDING MEANS.

Application filed July 6, 1925. Serial No. 41,537.

This invention relates to a winding machine and has more particularly reference to a reel for winding paper substantially uninterruptedly on a succession of winding shafts as the paper comes from a paper-making or other machine.

The chief problem presented in devices of this kind is to devise means whereby, after the paper has been wrapped around a winding shaft and the winding operation has commenced, the winding shaft may, during the winding operation, be moved over the surface of the winding means so as to enable a second winding shaft to be brought into position to take up the paper when the first shaft is full.

The main object and feature of this invention is to devise a machine in which the accumulation of paper on the winding shaft will automatically cause the latter to traverse the winding means during the winding operation.

In the accompanying drawings the invention is disclosed in a concrete and preferred form in which:

Fig. 1 is a side elevation, more or less diagrammatic in form, of a winding machine embodying the invention.

Fig. 2 is an end view looking in the direction of arrow 2 of Fig. 1.

Fig. 3 is a sectional detail view of one end of the winding shaft.

Fig. 4 is a fragmentary view showing a modified form of the invention.

1 indicates a winding means here shown as a surface winding drum driven by any suitable means such as pulley 2. 3 is a winding shaft; and 4 are two curved guides into which the ends of the winding shaft extend. The guides have hinged portions 5 pivoted at 6 and a latch 7 is provided whereby when portions 5 are in their lowered position the latch will hold the parts locked. The winding shaft is introduced into the guides at the lower end thereof and at the right-hand side in Fig. 1 by opening the hinged portions 5. The paper is now threaded between the drum and the winding shaft and wrapped around the latter. As the material accumulates on the winding shaft, the latter will rise and will follow the curved path prescribed by the guides. As a result of this, the roll of paper will, during the winding action, traverse the winding means or will progress over the surface of the

drums until position α is reached when the paper may be severed transversely and winding may be commenced around a new winding shaft placed in position in the lower end of the guides. The finished roll of paper 60 may now be pushed by hand, or otherwise, until it comes in line with slots 60 and out of contact with the drum where it is left spinning until it comes to a state of rest, after which it may be removed through the 61 slots aforesaid.

The construction of the winding shaft is preferably as follows: 70 is a core on which is loosely mounted a sleeve 8 on which the paper is wound and, associated with this 70 sleeve, may be a brake or gear 9 that is used in a subsequent operation when unwinding the paper. Mounted fast on the core, at each end of the shaft, is a pinion 10 that engages with a stationary rack 11 adjacent 75 each guide. It will be seen, therefore, that pinions 10 are free to rotate in a direction opposite to that of sleeve 8. The racks and pinions act to keep the winding shaft parallel with the drum. Core 70 also carries 80 a hook or eye 12, loosely mounted; and attached to this hook may be flexible connections 13 that pass over idlers 14 and have counterweights 15 suspended therefrom to offset the weight of the accumulating material. Core 70 may further be provided with antifriction rollers 16 that engage the guides. Hooks 12, in addition to acting as a means for attaching counterweights, may also be used as hook holds for the chains of a crane 90 whereby the roll may be removed.

In Fig. 4 is shown a modification in which the guides have a recess 17 in which the winding shaft may be supported initially out of contact with the drum and in connection 95 therewith may be used a roll 18 suitably driven that acts to initiate the winding operation before the winding shaft engages the drum.

I claim:

1. A winding machine including: surface winding means, a winding shaft to be placed in winding relation therewith, and guiding means for the shaft whereby the accumulation of material on the shaft causes it to 105 progress over the surface of the winding means.

2. A winding machine including: a surface winding drum, a winding shaft to be placed in winding relation therewith, and guiding 110

- means for the shaft whereby the accumulation of material on the shaft causes it to progress over the surface of the winding drum.
5. 3. A winding machine including: surface winding means, a winding shaft to be placed in winding relation therewith, guiding means for the shaft whereby the accumulation of material on the shaft causes it to progress over the surface of the winding means, and means for keeping the winding shaft parallel with the winding means.
10. 4. A winding machine including: a surface winding drum, a winding shaft to be placed in winding relation therewith, guiding means for the shaft whereby the accumulation of material on the shaft causes it to progress over the surface of the winding drum, and means for keeping the winding shaft parallel with the winding drum.
15. 5. A winding machine including: surface winding means, a winding shaft to be placed in winding relation therewith, and curved guides for the opposite ends of the shaft whereby the accumulation of material on the shaft causes it to progress over the surface of the winding means.
20. 6. A winding machine including: a surface winding drum, a winding shaft to be placed in winding relation therewith, and curved guides for the opposite ends of the shaft whereby the accumulation of material on the shaft causes it to progress over the surface of the winding means.
25. 7. A winding machine including: surface winding means, a winding shaft to be placed in winding relation therewith, curved guides for the opposite ends of the shaft whereby the accumulation of material on the shaft causes it to progress over the surface of the winding means.
30. 8. A winding machine including: a surface winding drum, a winding shaft to be placed in winding relation therewith, curved guides for the opposite ends of the shaft whereby the accumulation of material on the shaft causes it to progress over the surface of the winding means, and a counterweight flexibly connected to the shaft.
35. 9. A winding machine including: surface winding means, a winding shaft to be placed in winding relation therewith, guiding means for the shaft whereby the accumulation of material on the shaft causes it to progress over the surface of the winding means, and a counterweight flexibly connected to the shaft.
10. 10. A winding machine including: a surface winding drum, a winding shaft to be placed in winding relation therewith, guiding means for the shaft whereby the accumulation of material on the shaft causes it to progress over the surface of the winding drum, and a counterweight flexibly connected to the shaft.

Signed at New York, in the borough of Brooklyn county of Kings and State of New York, this 2nd day of July, 1925.

WILLIAM M. STOCKER.
